SHOE LASTING AND WELTING MACHINE

Edward W. Koloske, Milwaukee, Wis., and Leonard S. Curtin, Belmont, Mass., assignors to United Shoe Machinery Corporation, Flemington, N. J., a corporation of New Jersey

Application March 25, 1941, Serial No. 385,124

11 Claims. (Cl. 12—6)

The present invention relates to improvements in machines for lasting and sewing shoes and more particularly to machines of the type disclosed in U. S. Letters Patent No. 2,246,993, granted June 24, 1941, on an application of James P. Fredericksen, in which the outturned marginal portions of a shoe upper are fastened to the marginal portions of a thin unchanneled midsole layer or canvas sheet before an outer sole is attached to complete the shoe.

In the machine of the Fredericksen patent, a shoe upper is lasted and sewn to a thin unchanneled midsole or a sheet of woven textile material mounted on the tread surface of a last. The seam is inserted at a distance from the break line formed by the meeting side and tread surfaces of the last, the spacing of the seam from said line being determined by the position in which the shoe is presented to the machine by the operator during sewing. With this machine, the position of the seam connecting the upper and insole may be regulated by the operator in a manner not possible where a heavy channeled insole is employed, and other advantages result, both in connection with the subsequent steps of manufacture and with the completed shoe. After sewing the shoe on the machine of the patent, the outsole of the shoe is most conveniently attached by cementing or by through-and-through fastenings, the exposed portions of which appear on the outsole and inside the completed shoe.

It is an object of the present invention to improve the operation of the machine disclosed in the patent so that a shoe having a midsole composed of a thin unchanneled sheet or layer of woven material may be completed by attaching an outsole according to the usual Goodyear method, in which the projecting marginal portions of the outsole are sewed to the marginal portion of a welt secured to the upper with the stitches appearing entirely outside the shoe. Another object of the invention is to provide a shoe lasting and sewing machine with a guide for directing a welt strip into such relation with the upper of a shoe and with a thin unchanneled sheet as a midsole or innersole that the welt will be drawn, together with the upper, around the break line of a last which supports the upper and sheet, the location of the seam and welt connecting the parts being regulated by the position in which the shoe is presented to the machine during sewing.

With these and other objects in view, the present invention contemplates the provision in a shoe lasting and sewing machine operating

10 along the break line of a last and having upper tensioning members for imparting a stretch to the upper and a midsole or innersole sheet at a distance from the last to cause the upper and sheet to gape at the tread surface side of the break line on the last, of means for directing a welt towards the point of operation of the stitch forming devices at such an angle that it is supported against the action of the stitch forming devices by the gaping portion of the upper and is drawn, together with the upper, around the break line on the last to the tread surface of the last by the pull of the stitches inserted. As herein-after described, the stitch forming devices consist of a needle at one side of the work and a looper at the opposite side, the welt being supported by the tensioned upper against the thrust of the needle as it first enters the work. When properly located with relation to the break line on the last before sewing, the welt is drawn around the break line into a position with its grain surface in contact with the upper to a position after sewing where the margin of the upper forms an angular flange against the edge of the welt. The completed seam thus sewn compares favorably in appearance with the best quality inseam inserted by a curved hook needle machine without the use of a heavy channeled insole ordinarily required for this type of work.

20 30 35 40 45 With a curved needle sewing machine, the stitches are set into the materials operated upon more deeply than with a straight needle machine, particularly when attaching a welt. With the machine of the present invention, the line of stitches is deflected out of the path of the needle as they are being tightened so that a deep seam results with many of the advantages derived from the use of a curved needle machine. To assist in proper location of the welt in the machine, the position of the welt guide is made adjustable and, as in the machine of the patent referred to, the upper tensioning means comprises gripping rolls, one of which rotates on a stud carrying the welt guide at one end.

50 55 Other features of the invention consist of certain novel constructions, combinations and arrangements of parts hereinafter described and claimed, the advantages of which will be apparent to those skilled in the art from the following description and the accompanying drawings, in which Fig. 1 is a view in side elevation, partly broken away and in section, of the operating devices of a lasting and sewing machine embodying the features of the present invention; Fig. 2 is a view in front elevation of the upper tension-

ing rolls and stitch forming devices of the machine illustrated in Fig. 1, indicating a portion of a shoe being operated upon partially in section; Fig. 3 is a detail view of one end of a tensioning roll supporting stud in the machine; Fig. 4 is a detail sectional view illustrating the manner of operation of the machine taken somewhat in advance of the sewing point; and Fig. 5 is a similar view illustrating the positions of the parts in a shoe after being sewn.

The illustrated machine operates to sew a shoe upper in lasted relation with a thin unchanneled sheet of canvas material mounted on the tread surface of the last on which the shoe is constructed, together with one edge of a welt, in such a way that the resulting shoe has an appearance similar to that of a shoe manufactured according to accepted Goodyear welt shoe making practices. The corner portion of a last used in the construction of a shoe is indicated at 2 in Fig. 5, an upper including the lining at 4, a mid-sole member in the form of a canvas sheet to which the upper is lasted at 6 and a welt at 8. The canvas sheet is unchanneled and not pre-formed in any way, being cemented or tacked to the bottom or tread surface 10 on the last with flexible marginal portions extending loosely beyond the edges of a slightly beveled inner sole 12 also mounted on the tread surface of the last beneath the canvas sheet. Before the lasting and sewing operations, the upper and lining also are temporarily secured in place, leaving the marginal portions extending free along a break line 14 of the last formed by the angle between the upper supporting or side surface 16 and the tread surface 10 of the last. As thus far described, the construction of the shoe is similar to that disclosed in the patent above identified.

In order to construct a shoe, the outsole of which may be attached in a manner similar to Goodyear shoe making practices in the machine of the present invention, the welt 8 is positioned so as to be included in the seam 18 connecting the upper and canvas sheet 6 in such a way that it is drawn from a position where it is supported at the side of the last, as indicated in Fig. 4, around the break line onto the tread surface of the last, together with the upper, by the pull of the stitches, as in Fig. 5. To obtain this result, the position assumed by the free edge of the welt as it is led towards the sewing point in the machine is at an acute angle with the upper and the edge of the welt through which the seam passes is supported by the upper against the action of the stitch forming devices in the machine (see Fig. 4). When supported in this manner, the pull of the stitches inserted produces an angular flange on the upper extending from the tread surface of the last, and lying against the edge of the welt being sewn, the grain surface on the welt lying parallel to the tread surface of the last so that the free edge of the welt may be sewed to the projecting marginal portion of an outsole fitted to the shoe. The extending flange along the margin of the upper may be trimmed in the usual way before the outsole is fitted in place and the stitches of the seam 18 will appear to be similar to those inserted by a Goodyear inseam sewing machine.

The illustrated lasting and sewing machine is of the type disclosed in U. S. Letters Patent to Leveque No. 1,864,510 of June 21, 1932, except for the reduction in thickness and in width of the work support, according to the construction disclosed in the Fredericksen patent, and for

the provision of a guide 20 for the welt 8. Briefly, the machine is provided with a pair of upper tensioning rolls 22 and 24 acting with a continuous bite on the upper and canvas sheet or sole member a short distance from the break line 14 of the last to draw the marginal portions of the upper into conforming relation with the side surfaces of the last and to cause the upper and sheet to gape along the tread surface of the last in advance of the sewing point. The roll 22 is rotatably supported on a stud 26 having an enlargement at its forward end and is yieldingly pressed by a spring 28 towards the roll 24 to grip the parts operated upon. The stitch forming devices include a straight eye pointed needle 30 and a looper 32 mounted to rotate concentrically with the axis of rotation of the roll 24, the shoe being supported in a position to cause the needle to operate in a path approximately parallel to the tread surface 10 on the last.

The welt guide 20 is adjustably mounted on the enlargement at the free end of the stud 26, which enlargement has a lug portion for supporting a block 34 having a vertical slot 35 through which a clamp screw 36 passes into the lug on the enlargement. The welt guide which is formed from an angularly bent plate is secured at one end by a screw 38 passing through a slot in the welt guide plate and into threaded engagement with the block 34. The other end of the welt guide plate is provided with a pair of side flanges between which is adjustably clamped a welt edge engaging member 40 arranged to overlie the flesh surface of the welt, a shoulder 35 42 being formed to engage the edge of the welt and locate it within the guide. Along its central portion, the plate curves inwardly past the edge of the enlargement on the stud 26 and enters a circular recess 43 in the feed roll 22. As a means for holding the edge of the welt being sewed in position, the enlargement at the end of the stud has a forwardly projecting lug 44 which overlies the edge of the welt and also assists in guiding the needle as it enters the work. The welt 8, as it passes through the guide, is directed at an acute angle with relation to the portion of the upper which conforms with the side surface of the last and with the needle path indicated by the dot-dash lines 46 (Fig. 4), so that the needle will enter a stitch receiving groove 47 of the usual form along the edge of the welt and will emerge at or adjacent to the edge surface of the welt which is supported against the needle thrust, in part by the portion of the upper conforming with the side 16 of the last and in part by the tensioned portion of the upper which gapes away from the last. After the needle has penetrated the welt, the upper and the canvas sheet, the loop formed by the needle is transferred to the looper 32 and the needle retracted. During the retracting stroke of the needle, the stitch being formed is set.

As each stitch is set, the pull on the thread exerted by the stitch forming devices including the looper 32 causes the welt, together with the upper, to be drawn around the break line of the last and onto the tread surface of the last, the grain surface of the welt being brought into contact with that portion of the upper which is carried around the break line on the last. Since the needle is disengaged from the work, the work is no longer reinforced by the needle. The welt, in being drawn around the last break line, then causes the thread of the stitch being formed to be deflected so that the exposed portion of

thread on the welt is displaced from the needle path. As a result, the stitches are curved in a manner somewhat like those inserted by a curved needle machine.

If no welt is used in the construction of the shoe, the outer surface of the welt guide acts on the last conforming portion of the upper and the adjustable mounting of the guide is particularly useful in regulating the distance between the bite of the upper tensioning rolls and the break line of the last. To engage the last conforming portion of the upper surface with a substantial area of contact so as not to injure the surface of the upper, the welt guide plate has a round edged wing 48 extending towards the needle path. The position of the welt guide with respect to the upper is such that there is a suitable area of contact between the upper and the lower end of the wing 48, the welt guide being disposed at an angle with the line of feed both horizontally and forwardly and rearwardly of the machine.

By loosening the clamp screws 36 and 38, the position of the welt guide may be changed sufficiently to accommodate a wide range of shoe styles and sizes, as well as thicknesses in the materials operated upon. The adjustments of the welt guide obtainable include changes in position angularly about the clamp screw 38 which sets at right angles to the line of feed and angularly about the clamp screw 36 which is parallel to the axis of the feed roll stud 26. Also as a result of the slots through which the clamp screws pass, the welt guide may be shifted without changing its angular position in directions both parallel to the feed roll stud as well as at right angles thereto. Such changes in position are useful when sewing welts, as well as when no welt is employed to assist in presenting the upper and canvas sheet properly and with the desired amount of tension while sewing.

The nature and scope of the invention having been indicated, and a construction embodying the several features of the invention having been specifically described, what is claimed is:

1. A machine for lasting a shoe upper and attaching the upper and a welt to the marginal portions of an unchanneled sole member of relatively flexible material mounted on the tread surface of a last having, in combination, stitch forming devices operating along the break line formed by the angle between the side and tread surface of the last, means including upper tensioning members on the machine for imparting a stretch to the upper and sole member at a distance from the last to cause the upper and sole member to gape at the tread surface side of the break line on the last in advance of the point of operation of the stitch forming devices, and means for directing a welt towards the point of operation of the stitch forming devices at such an angle that the welt is supported by the gaping portion of the upper against the action of the stitch forming devices and is drawn, together with the upper, around the break line of the last onto the tread surface of the last by the pull of the stitches.

2. A machine for lasting a shoe upper and attaching the upper and a welt to the marginal portion of an unchanneled sole member of relatively flexible material mounted on the tread surface of a last having, in combination, stitch forming devices including a needle operating along the break line formed by the angle between the side and tread surfaces of the last, means including upper tensioning members on the ma-

chine for imparting a stretch to the upper and sole member at a distance from the last to cause the upper and sole member to gape at the tread surface side of the break line on the last in advance of the path of the needle, and means for directing a welt towards the needle path at such an angle that the welt is supported by the tensioned upper against the thrust of the needle and is drawn, together with the upper, around the break line of the last onto the tread surface of the last by the pull of the stitches inserted by the needle.

3. A machine for lasting a shoe upper and attaching the upper and a welt to the marginal portion of an unchanneled sole member of relatively flexible material mounted on the tread surface of a last having, in combination, stitch forming devices including a needle operating along the break line formed by the angle between the side and tread surfaces of the last, means including upper tensioning members on the machine for imparting a stretch to the upper and sole member at a distance from the last to cause the upper and sole member to gape at the tread surface side of the break line on the last in advance of the path of the needle, and means for directing a welt towards the point of operation of the needle at such an angle that one edge surface of the welt is supported against the thrust of the needle by the tensioned upper and is drawn by the pull of the stitches inserted by the needle around the break line to a position where the grain surface on the welt is brought into contact with that portion of the upper which is carried around the break line on the last and the marginal portion of the upper forms an angular flange against the edge of the welt extending from the tread surface of the last.

4. A machine for lasting a shoe upper and attaching the upper and a welt to the marginal portion of an unchanneled sole member of relatively flexible material mounted on the tread surface of a last having, in combination, stitch forming devices including a needle operating along the break line formed by the angle between the side and tread surfaces of the last, means including upper tensioning members on the machine for imparting a stretch to the upper and sole member at a distance from the last to cause the upper and sole member to gape at the tread surface side of the break line on the last in advance of the path of the needle, and a guide for directing a welt towards the point of operation of the needle at such a location that the welt is supported against the thrust of the needle in part by the last conforming surface of the upper and in part by the gaping portion of the upper and the welt is drawn by the pull of the stitches inserted by the needle around the break line onto the tread surface of the last to form an angular flange of the upper extending from the tread surface on the last with the grain surface on the welt in contact with that portion of the upper on the tread surface.

5. A machine for lasting a shoe upper and attaching the upper and a welt to the marginal portion of an unchanneled sole member of relatively flexible material mounted on the tread surface of a last having, in combination, stitch forming devices including a needle operating along the break line formed by the angle between the side and tread surfaces of the last, means including upper tensioning members on the machine for imparting a stretch to the upper and sole member at a distance from the last to cause

the upper and sole member to gape at the tread surface side of the break line on the last in advance of the path of the needle, and supporting and guiding means against which the last conforming surfaces of the sole member and upper are drawn by the upper tensioning members including a guide for directing a welt towards the point of operation of the needle so located that the welt is drawn by the pull of the stitches inserted by the needle around the break line of the last onto that portion of the upper supported by the tread surface of the last and the line of stitches exposed on the welt is deflected out of the path of needle operation.

6. A machine for lasting a shoe upper and attaching the upper and a welt to the marginal portions of an unchanneled sole member of relatively flexible material mounted on the tread surface of a last having, in combination, stitch forming devices including a needle operating along a path approximately parallel to the portions of the sole member supported by the tread surface of the last, means including upper tensioning rolls for imparting a stretch to the upper and sole member at a distance from the last to cause the upper and sole member to gape at the tread surface side of the break line on the last in advance of the needle path, a stud for supporting one of the tensioning rolls, and means carried at one end of the roll supporting stud for directing a welt towards the needle path at such an angle that the welt is drawn by the pull of the stitches inserted by the needle around the break line of the last onto the tread surface, together with the upper.

7. A machine for lasting a shoe upper and attaching the upper and a welt to the marginal portions of an unchanneled sole member of relatively flexible material mounted on the tread surface of a last having, in combination, stitch forming devices including a needle operating along a path approximately parallel to the portions of the sole member supported by the tread surface of the last, means including upper tensioning rolls for imparting a stretch to the upper and sole member at a distance from the last to cause the upper and sole member to gape at the tread surface side of the break line on the last in advance of the needle path, a stud for supporting one of the tensioning rolls, and a welt guide secured to one end of the roll supporting stud arranged to direct one edge of a welt into the needle path and with the other edge extending away from the upper tensioning rolls at an acute angle to the side surface of the last.

8. A machine for lasting a shoe upper and attaching the upper and a welt to the marginal portions of an unchanneled sole member of relatively flexible material mounted on the tread surface of a last having, in combination, stitch forming devices including a needle operating along a path approximately parallel to the portions of the sole member supported by the tread surface of the last, means including upper tensioning rolls for imparting a stretch to the upper and sole member at a distance from the last to cause the upper and sole member to gape at the tread surface side of the break line on the last in advance of the needle path, a stud for supporting one of the tensioning rolls, a work support, and a welt guide secured to one end of the roll

supporting stud arranged to conduct a welt towards the needle path and to act with the work support against the last conforming surfaces of the upper and sole member to resist the pull of the tensioning rolls.

9. A machine for lasting a shoe upper and attaching the upper and a welt to the marginal portions of an unchanneled sole member of relatively flexible material mounted on the tread surface of a last having, in combination, stitch forming devices including a needle operating along a path approximately parallel to the portions of the sole member supported by the tread surface of the last, means including upper tensioning rolls for imparting a stretch to the upper and sole member at a distance from the last to cause the upper and sole member to gape at the tread surface side of the break line on the last in advance of the needle path, a stud for supporting one of the tensioning rolls, a work support, a disk-like enlargement at the end of the roll supporting stud, a guide on the enlargement arranged to direct a welt towards the needle path and to act with the work support against the last conforming surfaces of the upper and sole member to resist the pull of the upper tensioning rolls, and means for adjusting the guide to change the position of the break line on the last supported by the welt guide with respect to the needle path.

10. A machine for lasting a shoe upper and attaching the upper and a welt to the marginal portions of an unchanneled sole member of relatively flexible material mounted on the tread surface of a last having, in combination, stitch forming devices including a needle operating along a path approximately parallel to the portions of the sole member supported by the tread surface of the last, means including upper tensioning rolls for imparting a stretch to the upper and sole member at a distance from the last to cause the upper and sole member to gape at the tread surface side of the break line on the last in advance of the needle path, a stud for supporting one of the tensioning rolls, a work support, and an adjustable guide secured to one end of the roll supporting stud arranged to act with the work support against the last conforming surfaces of the upper and sole member to resist the pull of the tensioning rolls.

11. A machine for lasting a shoe upper and attaching the upper and a welt to the marginal portions of an unchanneled sole member of relatively flexible material mounted on the tread surface of a last having, in combination, stitch forming devices including a needle operating along a path approximately parallel to the portions of the sole member supported by the tread surface of the last, means including upper tensioning rolls for imparting a stretch to the upper and sole member at a distance from the last to cause the upper and sole member to gape at the tread surface side of the break line on the last in advance of the needle path, a stud for supporting one of the tensioning rolls, and a welt guide secured to one end of the roll supporting stud and a lug on the stud for holding the edge of the welt being sewed in position.

LEONARD S. CURTIN.
